United States Patent Office

Des. 197,585
Patented Feb. 25, 1964

197,585

SEWING MACHINE

Russell A. Fritts, Cranford, N.J., assignor to The Singer
Company, New York, N.Y., a corporation of New
Jersey

Filed Nov. 13, 1963, Ser. No. 77,414

Term of patent 14 years

(Cl. D70—1)

Fig. 1.

Fig. 2.

Fig. 3.

Fig. 4.

Fig. 5.

Fig. 6.

FIG. 1 is a front perspective view of a sewing machine showing my new design,
FIG. 2 is a front elevational view thereof,
FIG. 3 is a rear elevational view thereof,
FIG. 4 is a top plan view thereof,
FIG. 5 is a left-hand end elevational view thereof, and
FIG. 6 is a right-hand end elevational view thereof.

I claim:

The ornamental design for a sewing machine, substantially as shown.
